CONTAINER

Harry Sebell, Boston, Mass., assignor to Arthur H. Parker, Lexington, Mass.

Application May 27, 1938, Serial No. 210,389

5 Claims. (Cl. 221—27)

This invention relates to a container of the type illustrated in my co-pending application, Serial No. 207,053, filed May 10, 1938, and which comprises a nozzle housing secured to the top of the can and within which is normally concealed a pouring nozzle, said nozzle being held in its concealed position by a cap which is removably applied to the housing. The nozzle is backed by a spring so that when the cap is removed the 10 spring acts to project the nozzle outwardly through an opening in the housing and into pouring position.

One of the objects of the present invention is to provide an improved construction by which 15 the nozzle housing can be secured to the can after the latter has been filled, this construction having the advantage that the can can be filled through the same opening as that through which the contents are discharged.

20 In order to give an understanding of the invention I have illustrated in the drawing a selected embodiment thereof which will now be described after which the novel features will be pointed out in the appended claims.

25 In the drawing:

Fig. 1 is a sectional view through the upper portion of the can having my improvements applied thereto;

30 Fig. 2 is a sectional view showing the manner of securing the nozzle housing to the can body;

Fig. 3 is a sectional view showing the cap removed and the nozzle in pouring position.

In the drawing 1 indicates a can or container, the upper end 2 of which is provided with an 35 opening 3 through which the can may be filled and through which the contents may be discharged. Surrounding the opening 3 is a neck portion 4 having exterior screw threads. Said screw threads may conveniently be rolled into the 40 neck as is usual in the construction of cans or containers having a screw-threaded cap. This neck 4 is secured to the can end 2 in any suitable way, and as herein illustrated the can end is formed with the upstanding flange 5 surrounding the opening 3 which fits into the lower end 6 of the neck 4, said lower end 6 being soldered to the flange 5.

The nozzle housing within which the pouring nozzle is concealed is shown at 7. This nozzle housing is secured to the neck 4 but projects beyond the same and is provided with a nozzle-receiving opening 8 adapted to receive the pouring nozzle 9 which is normally concealed within the housing 7. This opening 8 is formed in the 55 side wall of the housing 7 and is located outside

of and beyond the neck 4. The nozzle 9 is backed by a spring 10 which normally urges the nozzle outwardly and the nozzle and the spring are guided by a guiding finger 11 in a manner illustrated in my above-mentioned co-pending application. This finger 11 constitutes one arm of a U-shaped member 12 which fits within the housing 7, the other member 13 of said U-shaped member lying against the upper end of the housing. Said U-shaped member may be secured to 10 the housing in any suitable way as by being frictionally held therein or by being soldered or spot welded thereto. The nozzle housing 7 is formed with a skirt portion 15 which fits within the upper end of the neck 4. Said neck 4 is formed 15 at its upper end with the flat seat portion 16 and the skirt 15 of the nozzle housing is provided with a slight exterior groove or depression 17 into which the inner edge of the seat portion 16 fits, the lower extremity of the skirt 15 having a 20 slightly larger diameter than the groove 17, as indicated at 18.

19 represents a removable cap for sealing the container. This cap is formed with an upper housing-receiving portion 20 of a size and shape 25 to fit over the housing 7 and with a screw-threaded skirt portion 21 adapted to have screw-threaded engagement with the neck 4. The cap 19 is also provided with a shoulder portion 22 that cooperates with the seat portion 16 of the 30 neck to make a tight joint. Either the upper surface of the seat portion 16 of the neck 4 or the under surface of the shoulder 22 of the cap 19 will be provided with a ring 23 of packing material so that when the cap is screwed tightly 35 to the neck the packing 23 will be compressed between the seat 16 and the shoulder 22, thus making a tight joint and sealing the can.

When the cap 19 is in place, as shown in Fig. 1, the nozzle 9 will be held in its retracted position 40 by the portion 20 of the cap. When the cap is removed, however, the nozzle will be automatically projected into its pouring position, as shown in Fig. 3, by the action of the spring 10.

One feature of the present invention relates 45 to a construction which provides for attaching the nozzle housing 7 to the neck 4 after the can has been filled.

The cans are shipped to the place where they 50 are to be filled with the cap 19 separate from the can body and with the nozzle housing 7 located within the cap, as shown in Fig. 2. This nozzle housing fits the portion 20 of the cap so snugly that the cap and the nozzle housing in 55

their assembled relation may be transported as a unit.

After the can has been filled through the opening 3 then the combined cap and nozzle-housing unit is applied to the can by screwing the skirt portion 21 of the cap onto the neck 4 of the can. As the cap is screwed home the portion 18 of the skirt 15 of the nozzle housing is forced into and through the opening in the seat portion 16 of the neck. This portion 18 of the nozzle housing is sufficiently resilient so that it will contract slightly as it is forced through the opening in the seat portion 16 and will then expand when the groove 17 of the housing registers with the seat portion 16. The nozzle housing is thus attached to the can by the operation of screwing the cap onto the neck, and this operation can be readily done after the can has been filled.

20 When the nozzle housing has once been attached to the neck as above described it will remain so attached when the cap 9 is removed.

It will be understood that the nozzle housing is provided with a vent opening indicated at 31, 25 through which air is admitted during the discharge of the contents of the can through the nozzle.

I claim:

1. A container having an opening in one end 30 surrounded by a screw-threaded neck, a nozzle housing secured to said neck at its upper end and extending beyond the neck, said housing being provided in its side wall beyond the neck with a nozzle-receiving opening, a nozzle within 35 the housing, a spring for projecting the nozzle through said opening, and a cap having a housing-receiving portion within which said housing is received and a screw-threaded skirt adapted to have screw-threaded engagement with the 40 neck.

2. A container having an opening in one end surrounded by a screw-threaded neck, a nozzle housing extending beyond the neck and having a nozzle-receiving opening in its side wall, a 45 nozzle within the housing extending transversely to the neck axis, a spring acting on the nozzle

for projecting it outwardly through said opening, said housing having a radially compressible skirt portion which is received within and is frictionally retained by the outer end of the neck.

3. A container having an opening in one end 5 surrounded by a screw-threaded neck, a nozzle housing extending beyond the neck and having a nozzle-receiving opening in its side wall, a nozzle within the housing, a spring acting on the nozzle for projecting it outwardly through 10 said opening, said housing having a radially compressible skirt portion which is received within and is frictionally retained by the outer end of the neck, and a cap having a body portion adapted to enclose said housing and also having 15 a screw-threaded skirt portion for screw-threaded engagement with said neck.

4. A container having an opening in one end 20 surrounded by a screw-threaded neck, the latter being provided at its outer end with an outwardly directed flange, a nozzle housing having a nozzle-receiving opening in its side-wall, a nozzle within the housing, a spring acting on the nozzle for projecting it outwardly through 25 said opening, said housing having at its lower end 25 a radially compressible skirt portion provided with an exterior groove, said skirt portion fitting tightly within the flange of the neck with the edge of the flange occupying said groove.

5. A container having an opening in one end 30 surrounded by a screw-threaded neck, the latter being provided at its outer end with an outwardly directed flange, a nozzle housing having a nozzle-receiving opening in its side-wall, a nozzle within the housing, a spring acting on the nozzle for projecting it outwardly through 35 said opening, said housing having at its lower end a radially compressible skirt portion provided with an exterior groove, said skirt portion fitting tightly within the flange of the neck with the 40 edge of the flange occupying said groove, and a removable cap having a body portion to receive the housing and having a screw-threaded skirt portion for screw-threaded engagement with 45 said neck.

HARRY SEBELL.
